CLAIM

The ornamental design for a wedge pipe hanger, as shown and described.

DESCRIPTION

FIG. 1 is a perspective view of the first embodiment of a wedge pipe hanger;

FIG. 2 is a front elevation view of a wedge pipe hanger of the first embodiment according to the present invention;

FIG. 3 is a right side elevation view of the wedge pipe hanger of the first embodiment according to the present invention;

FIG. 4 is a left side elevation view of the wedge pipe hanger of the first embodiment according to the present invention;

FIG. 5 is a bottom planar view of the wedge pipe hanger of the first embodiment according to the present invention;

FIG. 6 is a top planar view of the wedge pipe hanger of the first embodiment according to the present invention;

FIG. 7 is a perspective view of the second embodiment of a wedge pipe hanger;

FIG. 8 is a front elevation view of a wedge pipe hanger of the second embodiment according to the present invention;

FIG. 9 is a right side elevation view of the wedge pipe hanger of the second embodiment according to the present invention;

FIG. 10 is a left side elevation view of the wedge pipe hanger of the second embodiment according to the present invention;

FIG. 11 is a bottom planar view of the wedge pipe hanger of the second embodiment according to the present invention;

FIG. 12 is a top planar view of the wedge pipe hanger of the second embodiment according to the present invention; and,

FIG. 13 is a perspective view of the first embodiment of the wedge pipe hanger in use with a second pipe hanger.

The broken line of one side of the device showing in FIGS. 1-3, 7-9 and 13 is for the purpose of illustrating that this feature of the device could be cut or not be cut and forms no part of the claimed design. The broken line feature showing on the top of the device of FIGS. 1-4, 6-10, 12 and 13 is for the purpose of illustrating hardware for connection of the device and forms no part of the claimed design. The broken line of the bottom member of a device showing in FIG. 13 is for the purpose of illustrating the devices may be stacked and forms no part of the claimed design.
